UNITED STATES PATENT OFFICE.

ALBERT G. L. PIEPER, OF CHICAGO, ILLINOIS, ASSIGNOR OF ONE-HALF TO ROBERT HOFELLE, OF CHICAGO, ILLINOIS.

PUNCHING AND CUTTING TOOL.

Application filed December 21, 1923. Serial No. 682,081.

The invention relates to punching and cutting tools and its object is to provide means whereby such tools may be readily operated to make a cut through material, 5 such as cloth, paper or the like, or to form a succession of holes.

The invention consists in the several novel features hereinafter set forth and more particularly defined by the claims at the conclusion hereof.

In the drawings: Fig. 1 is a vertical section of a device embodying the invention and equipped with a knife-blade for cutting slits. Fig. 2 is a section taken on line 2—2 15 of Fig. 1. Fig. 3 is a section taken on line 3—3 of Fig. 1. Fig. 4 is a vertical section of a modified form of the invention, applied to a punch or perforating tool. Fig. 5 is a perspective of the supporting base shown in 20 Fig. 4. Fig. 6 is a section taken on line 6—6 of Fig. 5.

In Fig. 1, there is shown a device for vertically reciprocating a knife-blade 7. This device is supported by a ring 8 which is 25 adapted to be moved over the work in order to position the knife where the slit is to be made and to permit it to be readily moved from place to place to form slits at different places or a succession of connecting slits 30 when desired. A pair of posts 9 are fixedly secured in the ring 8. Knife 7 is removably secured by screws 11 to a cross-head 10. Adjacent the outer ends of the cross head, sleeves 12 are fixedly held in sockets adjacent the ends of the cross-head and these sleeves 35 are slidably mounted on the posts 9 to vertically guide the cross-head. The upper ends of sleeves 12 are each closed by a screw-plug 13. Springs 14 are interposed between the 40 plugs and the upper ends of the posts 9 respectively to retract or lift the cross-head and the cutter carried thereby. The ends of the knife 7 are preferably guided in grooves 15 formed in the posts.

A stem 18 has its lower end secured by a screw 19 in a bushing 20 which is held in a socket in the cross-head 10, so that the stem will be rigid with the cross-head. A weighted hammer, consisting of a sleeve 21, which is slidably mounted on the stem 18, and a knob 22, which is screw-threaded to the upper end of the sleeve, is adapted to impart a hammer blow to the cross-head 10 to drive the knife 7 through the work. A spring 23, 50 coiled around stem 18 and held in a socket in

sleeve 21 and knob 23, engages a pin 24 fixed to said stem and is adapted to retract or lift the hammer after a blow has been imparted thereto, to drive the cutter through the material. Bushing 20 is preferably formed of 60 hard metal and serves as an anvil to receive the hammer blow of the lower end of the sleeve 21.

In the operation of this form of the invention, the ring 8 is placed over and at the 65 desired point where the material is to be cut and its own weight will tend to retain it in its assigned position. The operator will then impart a blow or a succession of blows to the knob 22 and the impact of the hammer 70 against the bushing or anvil 20 will drive the knife 7 through the material. If a continuous cut is desired, the ring 8 may be moved relatively to the material, so that the slits formed in the work will connect with one 75 another for this purpose.

In Figs. 4, 5 and 6, the invention is applied to a punch 26. In this form of the invention, the base 8^a is formed with an arch 27. A guide bushing 28, through which the punch 80 26 passes, is removably held in a socket 29 in the arch, by a screw 30. Guide-posts 9^a are secured in the ring 8^a. A cross-head 10^a has affixed thereto sleeves 12^a which are 85 slidably guided by posts 9^a. Springs 14^a are provided to lift or retract the head and parts 90 connected thereto. The punch 26 is held in a chuck 29. A stem 18^a is fixed to the chuck and extends upwardly therefrom. Stem 18^a is suitably secured in the cross-head 10^a and 95 is provided with an anvil bushing 20^a. A hammer, consisting of a sleeve 21^a, a knob 22^a, and a retracting spring 23^a is applied to the stem 18^a in the same manner as heretofore described in connection with the form 100 of the invention illustrated in Fig. 1. In order to limit the downward movement of the punch 26, collars 31 are slidably mounted upon the guide rods 9^a and are adapted to be rigidly secured thereto in any desired 105 position by set screws 32.

In the operation of this form of the invention, the base 8^a is placed upon the material to be punched and positioned accordingly. The operator will then adjust the collars 31 to make the stroke of the punch the desired length, and impart a blow to the head 22^a, the impact of the hammer against the anvil 20^a causing the punch to be driven through the material. If holes of different 110
